UNITED STATES PATENT OFFICE.

TRIMBLE DE ROODE, OF NEW YORK, N. Y.

PENDULUM-ELECTRODE FOR SPARK-PLUGS.

1,162,850.

Specification of Letters Patent.

Patented Dec. 7, 1915.

Application filed April 6, 1912. Serial No. 688,830.

To all whom it may concern:

Be it known that I, TRIMBLE DE ROODE, a subject of the Queen of the Netherlands, residing in New York city, New York, have invented certain new and useful Improvements in Pendulum-Electrodes for Spark-Plugs, of which the following is a specification.

My present invention relates to improvements in ignition devices for gas and calorific engines, and especially to that type of ignition device known as spark plugs, such as are used in high tension jump spark systems.

15 In its preferred form, my invention comprises a pendulum electrode and, slightly eccentric to its arc of vibration, a fixed electrode, preferably arcuate and spaced from the pendulum the proper distance proportionated to the strength of the current to be used, to insure sparks of maximum efficiency.

20 One of the objects of my invention is to prevent the formation, during use, of soot bridges, and to remove insulating coatings that are apt to form between the two terminals in such devices, thereby obviating the necessity for constant removal of the plug for cleaning.

25 In devices of this type, the two sparking terminals are usually arranged in certain fixed relation to one another and have no provision for the prevention of the bridging of the two terminals by hydrocarbons, or other like troubles from lubricating oils.

30 As is well known in devices of this class, if the spark gap, which is customarily arranged between the two terminals, is obstructed by a bridge of soot or other spark preventing material, the intensely hot spark which usually fires the charge in the gas engine will not arc, or the current may be conducted by the soot bridge without igniting the gas charge in the cylinder. Also, 35 fixed terminal jump spark devices usually become coated after a period of use with a covering of oil or hydrocarbons thereby becoming more or less insulated and effectually preventing the formation of the necessary arc for firing the explosive gas charge.

40 The above noted defects are overcome in my improved plug by making the terminals movable as regards one another, either one or both of the said terminals being loosely 45 mounted and by the constant movement of

the members, which movement is caused by the vibration of the engine, the formation of insulating bridges of foreign material or coatings are overcome, the said movable terminal members constantly freeing themselves by the said movement. It is necessary, however, that during this movement or swinging of the terminal member or members, while swinging or stationary, they must always maintain a gap well within the 60 arcing strength of the current furnished to them, and to do this I have arranged in all of the modifications shown in the accompanying drawings a limiting stop means, which prevents the swinging terminals from coming into absolute contact with one another and at the same time control the maximum possible arcing gap.

45 In the accompanying drawings, Figure 1 shows a complete spark plug in section, with 75 a pendulum terminal. Figs. 2 and 3 are details of Fig. 1. Figs. 4, 5, 6, 7 and 8 show modifications of my device.

50 In Fig. 1 the plug is shown comprised of the central electrode 1 having the usual 80 thumb nut 2 mounted thereon for receiving one end of a wire or wire clip for transmitting current thereto. An insulating core portion 3, which may be made of any suitable insulating material, is seated in an outer 85 shell 4, the said core being held in its operative position by a threaded bushing 5 and the said core member being thereby locked against movement. At the lower end of the central electrode 1 is arranged a 90 swinging terminal member or pendulum electrode 6, which terminal member is so located and arranged as to be caused to swing or vibrate by the vibration of the engine. This vibration is restricted to a limited 95 amount so that at all times, and during its most violent movement, the annular spark gap 7 is always a fixed amount, it being impossible for the terminal member 6 to contact with the edge 8 at the lower portion of 100 the shell member 4, which forms the opposite terminal thereof. The limiting of this swinging or vibration is shown as being due to a flat portion 9 which is arranged at the bottom of the central electrode 1, and 105 during the oscillation of the said terminal pendulum 6 the flat portion intercepts the upper portion and prevents more than a limited movement thereof.

55 It will be observed that the sparking edge 8 110

of the fixed electrode is arcuate, nearly, but not quite concentric with the arc of vibration of the pendulum so that during its vibrations, its distance from said edge varies 5 within narrow limits and prevents the formation of soot bridges.

In Fig. 2 is shown a bottom view of the electrode 1 showing the grooves 10—10 cut in the head 11 thereof, together with the bore 12, by which the ball pendulum 6, Fig. 3, is attached to the electrode, the two arms 14 and 15 being forced together into the bore of the electrode head 11 when in assembled position. The ball pendulum is then freely 15 suspended in relation to the said terminal and is susceptible to vibratory movement. It will be noted that the grooves 10—10 and the bore 12 in the electrode head 11, Fig. 2, are larger than the cross sectional area of 20 the pendulum arms 14 and 15 thus giving the pendulum a universal motion, while limiting its vibrations.

In Fig. 4, like numbers are used to designate parts similar to those described for Fig. 25 1, with the exception that the central insulating core member 3 has a chambered portion 16 therein into which is set the electrode 1 with its head portion 11. The pendulum 6, however, is somewhat different in construction to that described for Fig. 1, the said difference being comprised of a cone-shaped neck portion 17 which is arranged between the said ball portion 6 and its retaining arms 14 and 15.

35 In Fig. 5 the arrangement of the core shell and electrode member, together with the movable terminal, is exactly the same as that described for Fig. 1, with the exception that the terminal 8 of the outer shell portion 4 is 40 of the familiar wire type, and is bent over in such a manner as to be within arcing distance of the pendulum 6 which is loosely attached to the central electrode 1.

In Fig. 6 the principal parts there shown 45 are the same as those described for Figs. 1 and 5, with the exception that another form of terminal member 8 is a part of or integral with the outer shell portion 4, and the limited movement of the loosely mounted 50 terminal member 6 never entirely closes the annular sparking gap 20 between the shell terminal 8 and the swinging terminal 6.

In the variant shown in Fig. 7, the fixed 55 terminal is a ball 21 on the axial conductor 1 and the pendulum is a bail 6, eccentric to the ball 21 and loosely mounted in suitable bearings 23 and 24 at the lower part of the outer shell 4. Any movement or vibration of the engine will cause the bail terminal 60 portion 6 to oscillate or rock to and fro.

Fig. 8 shows a variant in which the pendulum 6 is an inverted saucer or cone having an opening 26 at its upper portion, the said opening being somewhat larger in diameter 65 than the stud portion 11 on the cen-

tral electrode 1, thereby permitting a certain limited amount of vibratory movement, while providing an annular shaped sparking gap 7 between the lower portion of the outer shell member and the extreme edges of the 70 saucer shaped terminal or pendulum 6.

I claim broadly coacting sparking pendulum and fixed electrodes.

Having described my invention I claim:

1. The combination in a spark plug, comprising a pair of terminals having insulation therebetween, of a pivoted extension arranged on one of said terminals, and means to limit the radius of movement of said extension to a distance spaced apart from said other terminal.

2. The combination in a spark plug, comprising a pair of terminals having insulation therebetween, of a pivoted downwardly hanging extension arranged on one of said terminals, and means carried by said suspended extension to limit its radius of movement to a distance spaced apart from said other terminal.

3. The combination in a spark plug, comprising a pair of terminals having insulation therebetween, of a loosely suspended downwardly hanging extension arranged on one of said terminals, and means carried by said suspended extension and its point of attachment to limit the movement of said extension.

4. In a spark plug comprising a central insulating core, a shell member thereon, a bushing member for retaining and sealing said insulating core in said shell member, a central electrode fixedly mounted in said insulating core, one end of said electrode being arranged to receive therein a wire, the other end thereof having arranged thereon a swiveled terminal member, said swiveled terminal member being mounted in proximity to the terminal portion of said shell member, and a limiting means on said electrode whereby the said swiveled terminal member may be limited in its oscillations.

5. A sparking device comprising a freely swinging pendulum electrode and a fixed electrode insulated and spaced therefrom.

6. A sparking device comprising a freely swinging pendulum electrode and eccentric thereto and insulated and spaced therefrom, a fixed electrode.

7. In a sparking device a pair of spaced and insulated electrodes, one of said electrodes being a gravity controlled pendulum, and approach limit means adapted to limit the vibration of said pendulum and prevent contact between said electrodes.

8. A spark plug having an electrode and a weight unitarily connected thereto and means for oscillatably supporting said electrode and weight eccentrically of the center of mass of the same, a lateral movement of

- said plug being operative to oscillate said electrode.
9. A spark plug having electrodes supported thereon, one of which consists of an elongated freely swinging member, having a pivoted end which is situated in operative relation to the other electrode. 5
10. A spark plug comprising electrodes supported thereon one of which is relatively long and is loosely pivoted at one end leaving the other end free to swing by force of gravity only, and a horizontal pivot support for said pivoted electrode. 10
11. A spark plug of the character described having electrodes and means consisting of a depending weight carried by one of said electrodes for causing oscillation of the said electrode when the position of the said spark plug is altered with respect to 15 the direction of the force of gravity through said electrode and its depending weight.
12. A spark plug comprising a stationary member, a stationary electrode, a pendulum-like electrode one end of which is pivoted in operative relation to the stationary electrode, a horizontal pivot support for the said pendulum electrode, the depending end of the said pendulum-like electrode contacting with a stationary part of the said spark 20 plug to compel an oscillatory movement of the said pendulum-like oscillatory electrode and to prevent revolution thereof.
13. A spark plug comprising a stationary body portion, a stationary electrode axially situated with respect to said stationary member, an elongated electrode pivotally supported at one end in axial alinement with the said stationary member and the other end of said elongated electrode normally occupying a depending position. 25
14. A spark plug comprising a stationary body portion, a stationary electrode, and an electrode pivotally supported at one end in operative relation with said stationary electrode, the other end normally assuming a depending position, whereby the said electrode is caused to swing in an oscillatory path by the vibrations of the said plug. 30
15. A spark plug comprising a stationary body portion, a stationary electrode, and an elongated electrode pivotally supported at one end in operative relation with, and at a constant distance from, said stationary elec-
- trode, the other end normally assuming a depending position. 35
16. A spark plug provided with and supporting electrodes, one of which is pivoted to move freely and is provided with a normally depending portion whereby it oscillates as its position is altered with respect to the direction of the force of gravity therethrough. 40
17. A spark plug having an electrode and an extension unitarily connected thereto and means for oscillatably supporting said electrode and extension eccentrically of the center of mass of the same, a lateral movement of said plug being operative to oscillate said electrode. 45
18. A spark plug having an electrode and means for oscillatably supporting said electrode eccentrically of the center of mass of the same, a lateral movement of said plug being operative to oscillate said electrode. 50
19. A spark plug having electrodes supported thereon, one of which consists of a freely swinging member, having a pivoted end, which is situated in operative relation to the other electrode. 55
20. A spark plug comprising electrodes supported thereon, one of which is loosely pivoted at one end leaving the other end free to swing by force of gravity only, and a horizontal pivot support for said pivoted electrode. 60
21. A spark plug of the character described, having electrodes and means consisting of a depending extension carried by one of said electrodes for causing oscillation of the said electrode when the position of the said spark plug is altered with respect to the direction of the force of gravity through said electrode and its depending extension. 65
22. The combination in a spark plug, comprising a pair of terminals, of a loosely suspended extension arranged on one of said terminals, and means carried by said suspended extension and its point of attachment to limit the movement of said extension. 70
